UNITED STATES PATENT OFFICE.

JAMES W. GREEN, OF ST. LOUIS, MISSOURI.

DUST-GUARD.

SPECIFICATION forming part of Letters Patent No. 718,452, dated January 13, 1903.

Application filed February 24, 1902. Serial No. 95,475. (No model.)

To all whom it may concern:

Be it known that I, JAMES W. GREEN, of the city of St. Louis, State of Missouri, have invented certain new and useful Improvements in Dust-Guards, of which the following is a full, clear, and exact description, reference being had to the accompanying drawings, forming a part hereof.

My invention relates to automatically-adjustable dust-guards; and it consists of the novel construction, combination, and arrangement of parts hereinafter shown, described, and claimed.

My object is to construct an improved dust-guard for car-axles which will be automatically adjustable and which may be quickly repaired or renewed without removing the axle from the oil-box and bearing, and my invention consists of a dust-guard comprising a lower half, an upper half, which is a duplicate of said lower half and joined to the lower half by a half-lap or ship-lap joint, springs to press the lower half upwardly against the axle, springs to press the upper half downwardly against the axle, both halves or sections being reversible and interchangeable, and a removable bearing for the upper ends of said springs.

Figure 1 is a vertical longitudinal section 30 of the oil-box and bearing shown in elevation and the dust-guard being shown in cross-section. Fig. 2 is a cross-section, partly in elevation, through the axle and box and showing the dust-guard. Fig. 3 is a top plan view 35 of the box, showing the dust-guard in position, part of the box being broken away.

Referring to the drawings in detail, my improved automatically-adjustable dust-guard comprises the lower half 4, the duplicate and 40 interchangeable upper half 5, there being a half-lap or ship-lap joint 6 at the meeting edges of said half 4 with the said half 5 at the horizontal center of the axle 7, the springs 8 to press the lower half 4 upwardly against 45 the axle, the springs 9 to press the upper half downwardly against the axle, and the removable bearing-block 10 for the upper ends of said springs 9. The oil box or bearing 11 has a rectangular recess 12 at its inner end, said recess being crosswise of the axle and adapted to receive the dust-guard. The lower end of the recess 12 is closed by the wall 13, which forms a seat for the lower end of the springs 8. The dust-guard is

preferably made of wood, and the lower edge 55 of the lower half 4 is laminated by inserting the cross-piece 14, the grain of the said cross-piece running crosswise of the grain of said lower half 4, so as to stiffen and strengthen the part and prevent its warping and splitting. The upper edge of the upper half 5 is laminated by inserting the cross-piece 15. The springs 8 are expansive coil-springs, and the upper ends are straightened to a vertical position and driven into the cross-piece 14, 60 thus adjusting the springs to the dust-guard so that the springs are removed with the dust-guard. The springs 9 are likewise adjusted to the cross-piece 15 in the upper half 5. The bearing-block 10 is made of wood 65 and is driven into the upper end of the recess 12.

The springs 8 and 9 will hold the two halves of the dust-guard closely against the axle, and as the bearing wears the parts will be 70 moved toward each other to take up the lost motion. The principal wear will be on the upper half 5, and when this piece is worn out the bearing-block 10 may be removed and a new half 5 inserted without removing 75 the axle from the oil-box and bearing and a new block inserted, thus practically renewing the entire dust-guard.

The sections may be removed without removing the axle from the oil-box by first 80 "jacking up" the oil-box 11 in the usual manner, which will take the weight off of the brass, and then said brass may be readily removed in the customary manner, and then the box may be lowered sufficiently to permit 85 the lower section 4 to be readily removed at the inner end of the box, and all without removing the axle from the box.

I claim—

An improved dust-guard, composed of 90 duplicate, interchangeable and reversible sections of wood, the edges of which are reinforced by fixed cross-pieces 14, 15, and coiled springs 8 and 9, one end of each of which is straightened and driven into the said 95 fixed cross-pieces, substantially as specified.

In testimony whereof I affix my signature in presence of two witnesses.

JAMES W. GREEN.
